TOY MODEL AIRPLANE

David William Posner, Livingston, N.J., assignor to
Childhood Promotions, Inc., Livingston, N.J.

Filed Jan. 26, 1971, Ser. No. 109,992

Term of patent 14 years

Int. Cl. D21—01

U.S. Cl. D34—15

FIG. 1 is a top plan view of the toy model airplane showing my new design.

FIG. 2 is a right side elevational view of the toy model airplane of FIG. 1.

FIG. 3 is a front elevational view of the toy model airplane of the present invention.

FIG. 4 is a rear elevational view of the toy model airplane of the present invention.

FIG. 5 is a bottom plan view of the toy model airplane of the present invention.

FIG. 6 is a perspective view of the toy model airplane of the present invention.

A left side elevational view of the toy model airplane of FIG. 1 is a mirror image of the right side elevational view shown in FIG. 2.

I claim as my invention:

The ornamental design for a toy model airplane, substantially as shown and described.
